UNITED STATES PATENT OFFICE.

WILLIAM E. WHITE, OF CHICAGO, ILLINOIS.

CONCRETE HANGER.

Application filed May 3, 1922. Serial No. 558,134.

To all whom it may concern:

Be it known that I, WILLIAM E. WHITE, a citizen of the United States, and resident of Chicago, in the county of Cook and State 5 of Illinois, have invented a certain new and useful Improvement in a Concrete Hanger, of which the following is a specification.

My invention relates to hanger inserts and particularly to an improvement on the construction shown in my co-pending application 10 Serial No. 556,597, filed April 26, 1922.

The improvements herein claimed relate to the matter of simplicity and economy in the process of manufacture. One of the 15 objects is to provide a hanger element adapted for vertical sliding movement within the housing, the hanger having the functions of a ring but which is so constructed as to avoid the necessity for a welding operation 20 such as is required to produce a ring. Incidentally the construction contemplates the provision of hook members of such size and so located that the hanger element is non-rotatable within the housing and cannot be 25 come disengaged or misplaced in service.

Another object in my invention is to simplify the manner of construction and assembly of the housing employed.

The invention will be more readily understood by reference to the accompanying drawings, wherein,

Fig. 1 is a side elevation of a hanger constructed in accordance with my invention.

Fig. 2 is a view taken at right angles 35 thereto;

Fig. 3 is a top plan view thereof;

Fig. 4 is a transverse sectional view, and,

Fig. 5 is a vertical sectional view.

In the drawings it will be seen that I provide 40 a combined anchor and support consisting of a length of wire rod bent to form a loop, consisting of parallel legs 10, and a horizontal connecting portion 11. These parts, together with the laterally deflected portions 12, constitute the anchor of the device. The loop is contained within a housing which is formed by bending a flat strip of sheet metal into rectangular outline, as shown in Fig. 4, the marginal edge 13 being 45 overlapped, as shown in Figs. 3 and 4. Continuous grooves 14 are formed in the sides of the housing for the accommodation of parallel legs 10 of the anchor. The top is closed by utilizing the overlapping tongues 50 15, 16, respectively, integral with the side walls of the housing. The marginal edge 17 of the tongue 16 is bent downwardly, as shown in Fig. 5. In practice I have found it unnecessary to weld the overlapping parts as the housing is stable particularly after 60 the concrete is poured therearound. The construction is such that the pressing of the plastic material on the exterior walls tends to firmly hold the casing in the desired relation of parts. As an additional means of 65 retaining the casing in proper relation, I provide the fastening staple, the legs 18 of which straddle the housing and frictionally engage the side walls thereof, as best shown in Fig. 3. This staple is described in my 70 co-pending application heretofore referred to and serves the very useful purpose of retaining the hanger in position on a form prior to the pouring of the concrete.

The hanger element which constitutes one 75 of the novel features of this invention, is formed from a length of wire of substantial size and is bent to form a loop, as best shown in Fig. 2, the terminal portions 19, 20, being then oppositely bent to provide hooks. The 80 spaces within the hooks are in line, and the hooks engage with the horizontal portion 11 of the anchor, the hanger element and the anchor being engaged before the anchor loop is inserted within the housing. The 85 legs 21, 22, of the hanger are relatively angularly disposed, as best shown in Fig. 1, extending from the closed portion 23 of the hanger loop diagonally upward, the spread 90 of the hanger at the upper end being sufficient to permit the accommodation of the hanger within the casing. The widening of the hanger at its upper end and the provision of the wide hooks 19, 20, results in a generally square outline, as best shown in 95 Fig. 4, which while it fits within the housing renders the hanger incapable of rotation therein. Thus the hanger may be raised to the dotted line position of Fig. 1, as is necessary when the insert is applied 100 to a form, yet it obviates any possibility of failure to properly cooperate with the anchor loop when the hanger is dropped to its operative position. In other words, the hooks on the upper ends of the hanger cannot fail to engage the anchor nor can the hanger be disengaged or dislocated without complete dismantling of the device. The parts may therefore be assembled as 105 shown and shipped and handled without the possibility of any of the parts becoming 110 disengaged or misplaced.

The advantage in constructing the hanger element in the manner shown is in that it may be produced in an automatic wire machine and no further operations such as 5 welding are necessary. In fact, the entire device is constructed on automatic machines and the manufacturing cost is thereby greatly reduced.

Obviously the construction is capable of 10 much modification and I do not wish to be limited except as indicated in the appended claims.

I claim:

1. In a hanger insert, the combination 15 of an anchor having a loop, a housing within which the loop is accommodated, said housing being of rectangular outline in cross section, and a hanger engaging said anchor loop and consisting of a length of wire 20 doubled on itself and with its ends bent to form oppositely projecting hooks, the lateral dimensions of the hooks being such that the hanger cannot rotate sufficiently within the rectangular casing to permit disengagement of the hooks from the loop.

2. In a hanger insert, the combination of 25 an anchor having a loop, a housing within which the loop is accommodated, and a hanger engaging said anchor loop and consisting of a length of wire doubled on itself and with its ends bent to form spaced apart 30 oppositely projecting hooks, the clearance between the walls of the housing and the lateral limits of the hanger being insufficient to permit rotation of the hanger.

3. In a hanger insert, the combination of 35 an anchor providing a depending loop, a

housing enclosing said loop, and a hanger 40 consisting of a length of wire doubled into a loop and having hooks on its ends for engagement with said depending loop, the clearance between the walls of the housing and the lateral limits of the hanger being insufficient to permit rotation of the hanger.

4. In a hanger, an anchor, a hanger element, and a housing providing a space within which the hanger may be received, 45 said housing consisting of a sheet of material bent into generally tubular form and provided with a pair of continuous longitudinal grooves in opposite side walls, and a pair of oppositely positioned integral lips for closing the otherwise open end of the thus formed housing.

5. In a hanger, an anchor including a depending loop, a housing providing grooves 50 interiorly thereof for accommodating parallel portions of the loop, an integral lip for closing the otherwise open upper end of the housing, and a swinging hanger mounted 55 on said depending loop.

6. In a hanger, the combination of an anchor having a depending loop, a housing 60 provided with internal groove for accommodating the parallel portions of the loop, means for closing the upper end of the housing, a hanger element suspended from said loop, and a staple straddling said casing and 65 serving to retain in place the means for closing the upper end of the casing.

Signed at Chicago, Illinois, this 28th day of April, 1922.

WILLIAM E. WHITE.
